Davis, Von, "Pin Removal Tool," U.S. Appl. No. 29/776,609, filed Mar. 31, 2021.

Primary Examiner — Philip S Hyder

(74) *Attorney, Agent, or Firm* — Lerner David LLP

(57) **CLAIM**

The ornamental design for a pin removal tool, as shown and described.

DESCRIPTION

FIG. 1 is a front, top perspective view of a pin removal tool according to my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear, bottom perspective view thereof.

The broken lines in the drawings having short segments illustrate portions of the pin removal tool that form no part of the claimed design. The broken lines in the drawings having long segments represent a boundary that forms no part of the claimed design.
